Primary Examiner — Aula Soroush(74) Attorney, Agent, or Firm — Gearhart Law LLC(57) CLAIM

The ornamental design for a bed for animal, as shown and described.

DESCRIPTION

FIG. 1 is a first perspective view of the bed for animal.

FIG. 2 is a second perspective view thereof.

FIG. 3 is a front view thereof.

FIG. 4 is a back view thereof.

FIG. 5 is a side view thereof. The other side view is identical to the side view of FIG. 5 and is therefore not shown.

FIG. 6 is a top view thereof; and,

FIG. 7 is a bottom view thereof.

1 Claim, 7 Drawing Sheets(56)
